UNITED STATES PATENT OFFICE.

STAFFORD LIGHTBURNE, JR., OF ST. LOUIS, MISSOURI.

REMINDER FOR RESERVOIRS OF VAPOR-STOVES.

SPECIFICATION forming part of Letters Patent No. 367,306, dated July 26, 1887.

Application filed May 24, 1886. Serial No. 203,137. (No model.)

To all whom it may concern:

Be it known that I, STAFFORD LIGHTBURNE, Jr., of the city of St. Louis, in the State of Missouri, have invented a certain new and

5 useful Improvement in Reminders for Reservoirs of Vapor-Stoves, of which the following is a full, clear, and exact description, reference being had to the accompanying drawings forming part of this specification, and in

10 which—

Figure 1 is a side elevation of the reservoir of a gasoline-stove, part broken away to show my invention, which is applied thereto. Fig. 2 is a perspective view of my invention removed from the reservoir. Fig. 3 is a side view illustrating a modification of the invention. Fig. 4 is a bottom view of that shown in Figs. 1 and 2. Fig. 5 is a bottom view of that shown in Fig. 3.

20 My invention relates to reminders for reservoirs of gasoline-stoves, the object or purpose of which is to indicate to or remind the user of the stove that when the cap is removed from the reservoir to fill the latter with oil the burner should be closed or turned off; and my invention consists in features of novelty hereinafter fully described, and pointed out in

25 the claims.

Referring to the drawings, A represents the 30 reservoir of a gasoline-stove secured to a supply-pipe, B, as usual, and provided with a top plate, a, formed with a screw-threaded collar or nozzle, a', surrounding a filling-opening, a", closed by a screw-threaded cap, C.

35 Secured directly or indirectly to this cap is a tablet or plate, D, that preferably extends down into the reservoir, as shown in Fig. 1. Upon this plate or tablet are printed the words, "Close the burner," or like words, indicating the same instruction.

40 In order to fill the reservoir with oil, it is necessary to remove the cap C, and in doing so the plate or tablet D, secured thereto, is raised or drawn from the reservoir, and these 45 words are exposed to view to remind the person filling the reservoir that the burner should first be closed.

I prefer to secure a bell, E, to the bottom of the plate or tablet, which will further attract 50 the attention of the person filling the reservoir to the words on the tablet or plate and remind the user of the fact that the burners should be closed before the reservoir is filled. This is a simple and effective way of remind-

ing the person that the burner should be closed 55 before filling the reservoir, and practically adds nothing to the cost or weight of the stove.

As a modification of my preferred form, instead of securing the plate or tablet directly 60 to the cap C, I form an opening or slot, e, in the cap C, and pass the plate or tablet down through it, as shown in Figs. 3 and 5, having first secured to the upper end of the plate or tablet a hood, F, that is larger than the cap 65 C, and covers it when the plate or tablet is down in the reservoir. After the plate is passed through the cap the bell is connected. Thus, in order to remove the cap C, in this case it is necessary to lift the hood F, with the 70 plate or tablet, to a sufficient extent to give access to the cap, and in doing so, the words on the tablet or plate are exposed to remind the person about to fill the reservoir that the burners should be closed before even the cap 75 C is removed.

If preferred, the words on the tablet or plate could be omitted, and then the tablet would merely act as a connection between the bell and cap C or hood F, and the bell would 80 act as a reminder to the person about to fill the reservoir that the burner should be closed.

I claim as my invention—

1. The combination, with a cap for closing the filling-opening of a vapor-stove reservoir, 85 of a pendent tablet connected thereto, forming a reminder, substantially as described.

2. The combination, with a cap for closing the filling-opening of a vapor-stove reservoir, 90 of a pendent tablet connected thereto, provided with a bell forming a reminder, substantially as described.

3. The combination, with a cap for closing the filling-opening of a vapor-stove reservoir, 95 of a tablet connected thereto, having a hood by which it is supported and forming a reminder, substantially as described.

4. The combination, with a cap for closing the filling-opening of a vapor-stove reservoir, 100 of a tablet connected thereto, having a supporting-hood at one end and a bell at the other end and forming a reminder, substantially as described.

STAFFORD LIGHTBURNE, JR.

In presence of—

GEO. H. KNIGHT,
JOE. WAHLE.
